PRESSURE REDUCING DEVICE FOR
REFRIGERATING APPARATUSHerman M. Goldberg, Chicago, Ill., assignor to
Standard Refrigeration Company, Inc., Chi-
cago, Ill., a corporation of Illinois

Application April 15, 1949, Serial No. 87,815

5 Claims. (Cl. 138—43)

1

The present invention relates in general to refrigeration apparatus and particularly to an evaporator unit embodying a built-in restrictor valve for controlling the flow of refrigerant fluid therethrough.

Any refrigeration evaporator unit, regardless of the type employed, must have some type of restricting device which will control the amount of refrigerant fluid flowing into the unit. The present accepted expansion valve or the commonly used capillary tube have proven to have many attendant disadvantages. A principal disadvantage is that the capillary tube often becomes clogged with foreign matter in operation of the refrigeration system. The conventional capillary tube is extremely difficult, if not impossible, to clean, and therefore it must, of necessity, be replaced if it becomes clogged with foreign matter. Moreover, the inside dimension of the capillary tubing is exceedingly small, and therefore it is impossible to hold to uniformity of dimension within the length of tubing during the manufacture of the tubing.

It is therefore an important object of the present invention to provide means for circumventing the difficulty inherent in present restrictor valves and overcoming the inherent disadvantages thereof by the provision of a new and improved evaporator unit having a restrictor valve which is completely self-enclosed and which provides means by which the amount of refrigerant fluid flowing into the evaporator unit may be adjustably controlled to any required degree.

Another important object is the provision of an evaporator unit embodying a built-in restrictor valve which may be adjusted readily to produce the required pressure drop in the flow of refrigerant fluid before it enters the cooling coils of the evaporator unit.

A further object is the provision of an evaporator unit embodying a restrictor valve which may be disassembled easily to permit removal of foreign matter which has accumulated therein and to enable the parts therein to be cleaned.

A still further object is the provision of an evaporator unit having a refrigerant restrictor valve comprising a cylinder having a rod screw-threaded therein, the screw threads in the tubular body member and the screw threads on the rod being formed in such a manner that a uniform restricted passage is provided therebetween to permit the flow of the refrigerant therethrough as it progresses through the valve.

Still another object of the invention resides in the provision of a refrigerant valve having a uni-

2

formly restricted passage formed therein, the length of the passage being controllable so as to provide the required pressure drop for refrigerant fluid flowing therethrough.

3 A further object is the provision of a refrigerant restrictor valve which may be installed in or on any conventional refrigerant evaporator unit and which may be manufactured at relatively low cost.

10 Another object resides in the provision of a restrictor valve having a plurality of adjustments by means of a hollow concentric member having threaded engagement with an outer member, and a second concentric member adjustably disposed in the first hollow concentric member.

15 Numerous other objects and advantages will be apparent throughout the progress of the following specification.

20 The accompanying drawings illustrate a selected embodiment of the present invention, and the views therein are as follows.

25 Fig. 1 is a detail elevational view of one form of evaporator unit embodying the refrigerant restrictor valve which forms a part of the present invention;

Fig. 2 is a detail longitudinal section through the restrictor valve;

30 Fig. 3 is an enlarged detail fragmentary section showing certain parts of the restrictor valve;

Fig. 4 is a transverse section taken on the line 4—4 of Fig. 3;

35 Fig. 5 is a detail longitudinal sectional view of a modified form of a restrictor valve whereby a central member has axial adjustment with respect to a surrounding member and the surrounding member has axial adjustment with respect to an outer member; and

40 Fig. 6 is an elevational view showing a modified form in which the central axially arranged member may be adjusted longitudinally with respect to its cooperating member by means of adjustment means located exteriorly of the restrictor valve.

45 The particular embodiment of the invention herein illustrated for the purpose of describing the invention comprises an evaporator unit 1 of any suitable size or shape having a restrictor valve 2 mounted therein. An inlet tube 3 which may lead from the high pressure side of any suitable and conventional compressor unit (not shown) joins with the inlet end of the valve 2, as indicated at 4, Fig. 1. The valve 2 may join at its outlet end, as indicated at 5, with a refrigeration coil 6 which is mounted by any suitable means to either the interior or the exterior of

the evaporator unit 1. The present restrictor valve affords means for controlling the rate of flow and the pressure drop of refrigerant before it enters the coiled tubing 6 within the evaporator unit 1.

The restrictor 2 comprises an elongated tubular body or cylinder 7 having an axially extending main bore 8 which is provided with internal screw threads 9 throughout its entire length. The threads 9 are of the sharp V type, having sharp V-shaped roots 10 and sharp V-shaped crests 11, Figs. 2 and 3. The cylinder 7 may have external screw threads 12 at its inlet end to receive suitable screw threads 13 which are internally formed within a cap member 14. The cylinder 7 has a closure wall 15 at its outlet end (at the left, Fig. 2). The closure wall 15 has an integral connection with an outwardly projecting stub or neck 16 having an axial bore 17 which communicates at its inner end with the main bore 8 in the cylinder 7. The stub or neck 16 may have a plurality of externally formed screw threads 18 which are adapted to engage or grip suitable internal threads formed in the coiled tubing 6.

The V threads 9 in the valve cylinder 7 are adapted to engage screw threads 19 formed externally on an elongated internal plug or rod 20, which may be positioned within the main bore 8. The threads 19 on the plug 20 are provided with V-shaped roots 21 and flat crests 22. The shape of the threads 19 may be formed by any suitable means, such as by cutting V threads on the plug 20 and then grinding down the sharp crests to produce the flat crests 22, Figs. 2 and 3. The interfitting of the flat crests 22 of the threads 19, with the sharp V threads 9 forms a slender spiral passage 23 which is relatively triangular in cross section. This passage 23 affords a uniformly restricted course of passage for the flow of refrigerant fluid, as the refrigerant progressively flows from the inlet end of the valve 2 to the outlet end of the valve.

Means for permitting or effecting adjustment of the length of the passage 23 comprises a counter-bore 24 which is formed in the inlet end of the cylinder 7, the counter-bore 24 being coaxial with the main bore 8. A shoulder or step 25 is formed in the valve body 7 at the inner end of the counter-bore 24 to provide means for adjusting the length of the spiral passage 23, in that the degree of penetration of the plug 20 within the main bore 8 and beyond the shoulder or step 25 directly determines the amount of restriction offered to the flow of the refrigerant. The length of the restricting passage 23 increases, therefore, when the plug 20 is screwed into the main bore 8, and decreases when the plug is screwed outwardly of the main bore 8.

A seal or washer 26 may be positioned between the cap member 14 and the inlet end of the cylinder 7, to provide a leak-proof hermetical seal between the cylinder and the cap member. The cap member 14 may have an annular grooved formed therein to receive the washer 26.

The cap member 14 carries an axially aligned stud or neck 27 which projects outwardly therefrom. The neck or stud 27 may have external screw threads 28 which are adapted to engage corresponding screw threads 29 formed on the inner surface of a closure cap 30. A passage 31 extending axially through the cap 14, and through the neck or stud 27, permits the user or service man to insert a screw driver, or any other suitable tool therethrough, when the cap

30 is unscrewed and removed from the stud 27, to engage a suitably shaped kerf or slot 32 formed in the proximate end of the rod 20. After the user or service man has inserted an appropriate tool, such as a screw driver, into the kerf or slot 32, he may adjust the length of the restricted passage 23 and, consequently, the flow and pressure drop of the refrigerant fluid passing therethrough, by merely rotating the tool in the proper direction until the desired pressure drop is obtained when the refrigeration system is in operation.

A seal or washer 33 may surround the neck or stud 27 to form a leak-proof hermetical seal between the cap member 14 and the cap 30 when the cap 30 is threaded on the stud 27.

A passage 34 through which refrigerant may enter the device is formed in the cap member 14. This passage 34 extends laterally from the passage 31 and communicates therewith. The passage 34 may have a suitable screening material 35, such as wire gauze, inserted therein for the purpose of separating foreign or extraneous matter from the refrigerant before it passes through the valve 2, so that the device may not become clogged. The screening material 35 may be removed periodically from the passage 34, so that this material may be cleaned or replaced with new screening material.

30 The end of the inlet tubing 3 has communication with the passage 34, and may be joined to the cap member 14 by any suitable means such as by soldering or the like.

The rod or plug 20 may be solid, but it is desirable and preferable that it be provided with a longitudinally extending bore 37 which communicates with the space or expansion chamber 36, Fig. 2, at the left end thereof. The bore is closed at its inlet end as shown in Figs. 2 and 3. 40 The bore 37 permits the refrigerant fluid to expand to a greater extent so that the temperature drop of the expanding refrigerant will be considerable. It is not altogether necessary, however, that the rod or plug 20 be provided with the bore 37, as it may be solid, whereby the chamber 36 alone may be used for the expansion of the refrigerant.

The pressure reducing or restricting valve 2 serves as an extremely effective means for controlling the flow of refrigerant entering the coil tubing 6 of the evaporator unit 1. Liquid refrigerant, which has been put under pressure by means of the usual compressor in the refrigerant system, enters the passage 34 from the tubing 3 and passes through the screening material 35 where any foreign matter which might be intermixed with the refrigerant is screened or separated therefrom. The liquid refrigerant then flows through the passage 31 and thence into the counter-bore 24 in the cylinder 7. Upon arriving at the shoulder 25 at the inner end of the counter-bore 24 the refrigerant enters and progresses through the spiral passage 23 formed between the screw threads 9 and 19 in the cylinder 7 and on the plug or rod 20, respectively. The pressure of the refrigerant is reduced successively as the refrigerant flows through the passage 23, the amount of pressure drop being determined by the depth of penetration of the plug or rod 20 in the threaded bore 8 of the cylinder 7. As the liquid refrigerant reaches the end of the spiral passage 23, it expands immediately into the space 36 which is formed in the bore 8 between the left hand end of the rod 20 and the closure wall 15. This space 36 forms an expansion

sion chamber for the refrigerant. The expanded refrigerant, which has changed into the gaseous state, then flows through the bore 17 and into the coiled tubing 6 where it further expands and absorbs heat from the surroundings. By the time the refrigerant reaches the coil tubing 6, it is in a gaseous state and is drawn into the compressor where its pressure is increased, thereby causing the refrigerant to condense and change back into the liquid state.

The invention comprises a refrigeration evaporator unit having a built-in restricting valve, which can be used with any type of refrigerant, since any desired pressure drop may be made by proper adjustment of the position of the plug or rod 20 in the main bore 8. The device may be easily disassembled for cleaning by first removing the cap member 14 from the cylindrical body 7 and then removing the threaded rod 20 from the bore 8 of the cylindrical body 7.

Many additional advantages arise by utilizing a device of the type embodied in the invention. Vibration noises which are familiar to capillary tube installations are eliminated, whether the device is used with a household standard temperature unit or with a plate type low temperature refrigeration unit. This novel type of evaporator unit having a built-in pressure reducing valve balances the load on the compressor motor on the off-cycle. Motors having low starting torques may be used because of this balancing feature, therefore, and the cost of manufacturing the refrigeration system is correspondingly lower. Also the use of the present unit eliminates the use of a liquid receiver, and thereby less refrigerant is used or required for successful operation.

The modification shown in Figs. 5 and 6 comprises a cylindrical outer housing 38 which receives a cylindrical threaded member 39, the threaded member 39 being locked to the casing 38 in any convenient manner such as by set screws 40. The threaded member 39 has inner threads 41 which threadedly receive threads 42 on an interior threaded member 43. The threads 42 of the member 43 are flattened so that a continuous spiral passage is formed between the threads 41 and 42. The member 43 is also provided with threads 44 on its inner surface to cooperate with threads 45 on a central threaded plug 46. The threaded plug 46 is provided with exterior threads 47 which are flattened so that when the central plug 46 is threaded in the hollow member 43 a spiral passage will be formed about the central plug 46. The central plug 46 therefore has axial adjustment with respect to the surrounding member 43, and the surrounding member 43 has threaded adjustment with respect to the outer surrounding member 39. Therefore the members 46 and 43 each have separate and independent adjustment.

The outer casing 38 may be provided with a flange-like end or pad 48 to receive a fitting 49. The fitting 49 may comprise a cylindrical opening 50 leading to the interior of the restrictor valve, Figs. 5 and 6. Fluid entering the opening 50 will then pass about the spiral passage surrounding the plug 46 and enter the expansion chamber 51 at the opposite end. The fluid will then pass in the space 51 where it is free to pass through the spiral passage between the outside of the member 43 and the inside of the member 39. The fluid will then be collected in the chamber 52 and pass through the outlet 53.

The other end of the restrictor valve (to the right, Fig. 5) may be sealed by a threaded mem-

ber 54 threadedly engaging the outside of the outer casing 38. The member 54 terminates in a neck 55 which receives a threaded cap 56. The threaded cap 56 is adapted to be removed, and the central plug 46 may be adjusted by inserting a screw driver through the opening in the neck 55 and engaging the screw driver slot 57 formed in the right hand end of the plug 46.

The surrounding tubular member 43 may be 10 adjusted by the insertion of a proper tool through the neck 55 and engaging the multi-sided surfaces of the interior of the member 43, or if desired the member 43 may be provided with socket members 58 to receive a spanner wrench to effect 15 the adjustment. In this latter instance the entire outer cap 54 may be removed. However, the opening in the neck of the member 54 or the screw member 54 itself may be of such size and proportions as to permit a proper tool to be inserted 20 therein for effecting longitudinal or axial adjustment of the member 43 with respect to the member 39, the arrangement being such that the plug 46 may be adjusted with respect to the surrounding member 43 and the surrounding member 43 25 may be adjusted with respect to the outer member 39. The arrangement in Fig. 5, therefore, while being similar to the construction shown in Figs. 1-4, inclusive, provides for an additional adjustment.

The modification shown in Fig. 6 is for the purpose of adjusting the central screw plug 46 exteriorly of the restrictor valve. This latter construction discloses a screw member 59 which is arranged in the end flange or pad 48 of the housing 38. The inlet 50 may extend at right angles as shown in Fig. 6, and an extension rod 60 may be formed integral with the central plug 46 and extend through the end 61, there being a proper packing gland 62 and a lock nut 63 for preventing 30 the escape of fluid from the line 50.

The construction shown in Figs. 5 and 6, therefore, is adapted for double adjustment. The construction in Fig. 5 discloses an end cap for gaining access to the interior of the casing, while 35 the construction in Fig. 6 discloses an arrangement whereby the central plug may be adjusted exteriorly of the casing.

A first or main adjustment may be made of the surrounding member 43 with respect to its 40 cooperating member 39, and then when this adjustment is made it may be more or less permanent as the additional or finer adjustment may be made by adjusting the central plug 46.

The inner member 43, Fig. 5, may be reduced 45 as indicated at 64, Fig. 5, so as to provide a chamber between the inside of the member 39 and the outside of the member 43 as clearly shown at the left hand end of Fig. 5. In this latter event the screw threads 44 may be omitted 50 for a predetermined length commensurate with the length of the chamber 64.

The device embodied in the invention may be 55 manufactured at low cost and is extremely efficient in operation. The restricted spiral passage or passages 23 which produce the pressure drop are uniform in cross section throughout, thereby 60 overcoming the lack of uniformity found in ordinary capillary tubing. A production run of 65 evaporator units may be made, therefore, with 70 an assured pressure drop setting.

Changes may be made in the form, construction and arrangement of parts without departing 75 from the spirit of the invention or sacrificing any of its advantages, and the right is hereby

reserved to make all such changes as fall fairly in the scope of the following claims.

Having thus described my invention, what I claim as new and desire to secure by Letters Patent of the United States is:

1. A restrictor valve for refrigerating apparatus for controlling the flow of fluid in a refrigeration system comprising a centrally disposed tube having interior screw threads, a central plug having exterior screw threads engageable with the interior screw threads of the tubular member, the screw threads of one of said members being uniformly flattened to provide a spiral passage of uniform cross-section about the central plug, exterior screw threads on the tube and engaging screw threads on an outer surrounding member, the screw threads on one of said latter members being uniformly flattened to provide a spiral passage of uniform cross-section about the outside of the tube member.

2. A restrictor valve for refrigerating apparatus for controlling the flow of fluid in a refrigeration system comprising a centrally disposed tube having interior screw threads, a central plug having exterior screw threads engageable with the interior screw threads of the tubular member, the screw threads of one of said members being uniformly flattened to provide a spiral passage of uniform cross-section about the central plug, exterior screw threads on the tube and engaging screw threads on an outer surrounding member, the screw threads on one of said latter members being uniformly flattened to provide a spiral passage of uniform cross-section about the outside of the tube member, and means for adjusting the tubular member with respect to the outer surrounding member.

3. A restrictor valve for refrigerating apparatus for controlling the flow of fluid in a refrigeration system comprising a centrally disposed tube having interior screw threads, a central plug having exterior screw threads engageable with the interior screw threads of the tubular member, the screw threads of one of said members being uniformly flattened to provide a spiral passage of uniform cross-section about the central plug, exterior screw threads on the tube and engaging screw threads on an outer surrounding member, the screw threads on one of said latter members being uniformly flattened to provide a spiral passage of uniform cross-section about the outside of the tube member, and means for adjusting the central plug axially with respect to the surrounding tube.

4. A restrictor valve for refrigerating apparatus for controlling the flow of fluid in a refrigeration system comprising a centrally disposed tube having interior screw threads, a central plug having exterior screw threads engageable with the interior screw threads of the tubular member, the screw threads of one of said members being uniformly flattened to provide a spiral passage of uniform cross-section about the central plug, exterior screw threads on the tube and engaging screw threads on an outer surrounding member, the screw threads on one of said latter members being uniformly flattened to provide a spiral passage of uniform cross-section about the outside of the tube member, means for adjusting the tubular member with respect to the outer surrounding member, and means for adjusting the central plug axially with respect to the surrounding tube.
5. A restrictor valve for refrigerating apparatus for controlling the flow of fluid in a refrigeration system comprising a centrally disposed tube having interior screw threads, a central plug having exterior screw threads engageable with the interior screw threads of the tubular member, the screw threads of one of said members being uniformly flattened to provide a spiral passage of uniform cross-section about the central plug, exterior screw threads on the tube and engaging screw threads on an outer surrounding member, the screw threads on one of said latter members being uniformly flattened to provide a spiral passage of uniform cross-section about the outside of the tube member, means for adjusting the tubular member with respect to the outer surrounding member, and means for adjusting the central plug axially with respect to the surrounding tube.
20. 5. A restrictor valve for refrigerating apparatus for controlling the flow of fluid in a refrigeration system comprising a centrally disposed tube having interior screw threads, a central plug having exterior screw threads engageable with the interior screw threads of the tubular member, the screw threads of one of said members being uniformly flattened to provide a spiral passage of uniform cross-section about the central plug, exterior screw threads on the tube and engaging screw threads on an outer surrounding member, the screw threads on one of said latter members being uniformly flattened to provide a spiral passage of uniform cross-section about the outside of the tube member, means for adjusting the tubular member with respect to the outer surrounding member, and means for adjusting the central plug axially with respect to the surrounding tube, the adjusting means for the central threaded plug member extending outwardly of the body of the valve.
